CLAIM

The ornamental design for a filter unit, as shown.

DESCRIPTION

FIG. 1 is a perspective view of a filter unit of my new
appearance design as it appears in operation suspended
from overhead and with filter media in place;

FIG. 2 is an additional perspective view of the filter unit
of FIG. 1 showing the bottom, rear and opposite sides
not visible in FIG. 1; and

FIG. 3 is a perspective view from the same orientation
as FIG. 1, but showing the appearance of the filter unit
with the filter media and rolls removed.

FIG 1

FIG 2

FIG. 3
